His ATTORNEY

UNITED STATES PATENT OFFICE

CHARLES W. BELL, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF HIGHWAY CROSSING SIGNALS

Application filed October 22, 1930. Serial No. 490,456.

My invention relates to apparatus for the control of highway crossing signals, that is, signals located at intersections of railways and highways, and designed to indicate to those using the highway whether or not a train is approaching on the railway.

One object of my invention is to provide control apparatus which will permit the use, at intersections of railways and highways, of signals capable of displaying three separate and distinctive indications.

I will describe two forms of apparatus embodying my invention, and will then point out the novel features thereof in claims.

15 In the accompanying drawing, Fig. 1 is a diagrammatic view illustrating one form of apparatus embodying my invention. Fig. 2 is a similar view showing a modified form of the apparatus illustrated in Fig. 1, and 20 also embodying my invention.

Similar reference characters refer to similar parts in both views.

Referring first to Fig. 1, the reference characters 1 and 1^a designate the track rails 25 of a stretch of railway track which is intersected by a highway H, and over which traffic normally moves in both directions. Located on opposite sides of the railway adjacent the intersection of the railway and the highway 30 are two highway crossing signals S¹ and S², the function of which is to give a warning indication when a train is approaching the highway from either direction. These signals may be of any suitable type, but as 35 here shown, they are similar to those commonly employed at street intersections, and each comprises a proceed lamp G, a preliminary warning lamp Y, and a stop lamp R.

40 The track rails of the railway are divided, by means of insulated joints 2, to form a plurality of track sections D—E, E—F, F—J and J—K, the junction of the sections E—F and F—J preferably being located at or near the highway crossing H. Connected across 45 the rails of each section at the end farthest away from the highway is a suitable source of track circuit current, here shown as a track battery 3, and connected across the rails of sections D—E and J—K at the end 50 nearest the highway are two track relays T^E

and T^J, respectively. One magnet 4^a of an interlocking relay L¹ is connected with the rails of section E—F adjacent the highway H, and the other magnet 4^b is similarly connected with the rails of section F—J.

The interlocking relay L¹ may be of any of the well known types, such for example, as the relay illustrated in United States Letters Patent No. 799,452, granted to W. W. Coleman on September 12, 1905, and as here shown, is provided with two front contacts 6^a and 7^a and a back contact 8^a which are controlled by the magnet 4^a, and with two front contacts 6^b and 7^b and a back contact 8^b which are controlled by the magnet 4^b. If magnet 4^a becomes deenergized before magnet 4^b becomes deenergized, front contacts 6^a and 7^a will become opened, and back contact 8^a will become closed. If magnet 4^a becomes deenergized subsequent to magnet 4^b, however, front contacts 6^a and 7^a will become opened, but back contact 8^a will remain open. Similarly, if magnet 4^b becomes deenergized before the magnet 4^a, front contacts 6^b and 7^b will become opened and back contact 8^b will become closed, but if magnet 4^b becomes deenergized subsequent to magnet 4^a, front contacts 6^b and 7^b will become opened and contact 8^b will remain open.

The interlocking relay L¹ and the track 80 relays T^E and T^J control a second interlocking relay L² which is similar to the interlocking relay L¹, except that magnet 4^a of relay L² controls a "flagman" contact 9^a and a back contact 10^a while magnet 4^b controls a 85 "flagman" contact 9^b and a back contact 10^b. The back contacts 10^a and 10^b of the relay L² operate in the same manner as the back contacts 8^a and 8^b of the relay L¹. The flagman contacts 9, however, are so arranged that 90 these contacts will be closed either when the associated magnet is energized or has become deenergized subsequent to the deenergization of the other magnet but not when the associated magnet becomes deenergized while the other magnet is energized.

Magnet 4^a of interlocking relay L² is provided with a circuit which passes from terminal B of a suitable source of current not shown in the drawing, through front contact 100

- 11 of track relay T^E , front contact 6^a of interlocking relay L^1 , and magnet 4^a of interlocking relay L^2 to the other terminal C of the source. Similarly, magnet 4^b of interlocking relay L^2 is provided with a circuit which passes from terminal B, through front contact 12 of track relay T^V , front contact 6^b of interlocking relay L^1 , and magnet 4^b to terminal C.
- 10 The interlocking relays L^1 and L^2 jointly control the signals S^1 and S^2 . Considering signal S^1 , for example, the lamp G of this signal is provided with a circuit which passes from terminal B, through flagman contacts 9 a and 9 b of interlocking relay L^2 , and the filament of lamp G to terminal C. When this circuit is closed, lamp G is lighted and signal S^1 displays a proceed indication. The lamp Y of signal S^1 is provided with a circuit which passes from terminal B, through back contact 10 b of interlocking relay L^2 , front contact 7 b of interlocking relay L^1 , and the filament of lamp Y to terminal C. Lamp Y of signal S^1 is also provided with another circuit which passes from terminal B, through back contact 10 a of interlocking relay L^2 , front contact 7 a of interlocking relay L^1 , and the filament of lamp Y to terminal C. When either of the circuits just traced is closed, lamp Y is lighted, and signal S^1 displays a preliminary warning indication. The lamp R of signal S^1 is also provided with two circuits, one of which passes from terminal B, through back contact 8 a of interlocking relay L^1 , and the filament of lamp R to terminal C, and the other of which passes from terminal B, through back contact 8 b of interlocking relay L^1 , and the filament of lamp R to terminal C. When either of these circuits is closed, lamp R is lighted, and signal S^1 displays a stop indication. Each of the lamps of signal S^2 is connected in multiple with the corresponding lamp of signal S^1 , and it will be apparent therefore that when a lamp of one signal becomes lighted, the corresponding lamp of the other signal will also become lighted.
- As shown in the drawing, sections D—E, E—F, F—J and J—K are all unoccupied, so that track relays T^E and T^V , and both magnets 4^a and 4^b of interlocking relay L^1 are all energized. The circuits previously traced for the magnets 4^a and 4^b of interlocking relay L^2 are therefore closed, and both of these magnets are therefore energized. The circuits for the proceed lamps G of both signals S^1 and S^2 are therefore closed at flagman contacts 9 a and 9 b of interlocking relay L^2 and both of these lamps are lighted to indicate that traffic on the highway may proceed across the railway.
- I will now assume that a train moving from left to right enters section D—E. This will cause track relay T^E to become deenergized and open its front contact 11, which will interrupt the circuit for magnet 4^a of interlocking relay L^2 , and so deenergize this magnet. Flagman contact 9 a of relay L^2 will therefore become opened, and back contact 10 a will become closed. The opening of flagman contact 9 a will interrupt the circuit for the proceed lamps G of the signals S^1 and S^2 , and the closing of back contact 10 a will complete one of the circuits for the preliminary warning lamps Y of these signals. The proceed lamps G will therefore become extinguished, and the preliminary warning lamps Y will become lighted. The preliminary warning lamps will now remain lighted until the train enters section E—F and deenergizes magnet 4^a of interlocking relay L^1 . When this happens, front contacts 6 a and 7 a of interlocking relay L^1 will become opened, and back contact 8 a will become closed. The opening of front contact 6 a will interrupt the circuit for magnet 4^a of interlocking relay L^2 at this contact and, hence, will prevent this magnet from becoming energized when front contact 11 of track relay T^E subsequently becomes energized due to the rear end of the train having passed completely out of section D—E. The opening of front contact 7 a of interlocking relay L^1 will interrupt the circuit which was previously closed for the preliminary warning lamps Y at this contact, and the closing of back contact 8 a will complete one of the circuits for the stop lamps R. The preliminary warning lamps Y will therefore become extinguished, and the stop lamps R will become lighted. When the train enters section F—J, magnet 4^b of relay L^1 will become deenergized, so that relay L^1 will now open its front contacts 6 b and 7 b . The opening of front contact 6 a of interlocking relay L^1 will interrupt the circuit for magnet 4^b of interlocking relay L^2 , and this magnet will also become deenergized. Flagman contact 9 b of this relay will remain closed, however, and back contact 10 b will remain open under these conditions due to the operation of the relay pointed out hereinbefore. When the train has passed completely out of section E—F, magnet 4^a of interlocking relay L^1 will again become energized so that front contacts 6 a and 7 a will again become closed, and back contact 8 a will become opened. When back contact 8 a becomes opened, the circuit which was previously closed for the stop lamps R at this contact will be opened, and these lamps will become extinguished. Since front contact 11 of track relay T^E is now closed, the closing of front contact 6 a will complete the circuit for magnet 4^a of interlocking relay L^2 , and magnet 4^a will therefore become energized. Flagman contact 9 a will therefore become closed and back contact 10 a will become opened. The closing of flagman contact 9 a will complete the circuit for the proceed lamps G of signals S^1 and S^2 , and these lamps will therefore become lighted. When the

train enters section J—K, track relay T^j will become deenergized, and will open its front contact 12, but since the circuit for magnet 4^b of interlocking relay L^2 is already open 5 at front contact 6^b of interlocking relay L^1 , this will have no effect on the remainder of the apparatus. When the train passes out of section F—J, magnet 4^b will again become energized. This will cause front contacts 6^b 10 and 7^b to become closed but will otherwise have no effect on the apparatus. When the train has passed completely out of section J—K, track relay T^j will again become energized and will close its front contact 12. This 15 will cause magnet 4^b of interlocking relay L^2 to become energized, thereby restoring the parts to their normal positions in which they are illustrated in the drawing.

When a train moving from right to left 20 traverses the stretch of track illustrated in the drawing, the operation of the apparatus will be exactly the reverse of that just described, and will be readily understood from an inspection of the drawing without tracing 25 the sequence of operation in detail.

Referring now to Fig. 2, the apparatus here shown is similar to that shown in Fig. 1 with the exception that, as here shown, relay L^1 is provided, in addition to the contacts shown 30 in Fig. 1, with two flagman contacts 13^a and 13^b which operate in the same manner as the flagman contacts 9^a and 9^b of relay L^2 shown in Fig. 1, and which are utilized to control the proceed lamps G of the signals 35 S^1 and S^2 in place of the flagman contacts 9^a and 9^b shown in Fig. 1. The circuits for these lamps will be obvious from an inspection of the drawing.

With the apparatus constructed as shown 40 in Fig. 2, when a train moving toward the right enters section D—E and deenergizes track relay T^e , magnet 4^a of interlocking relay L^2 will become deenergized as before, and will close its back contact 10^a. This will 45 close one of the circuits for the preliminary warning lamps Y, and these lamps will become lighted. Since the proceed lamps G are now controlled by the flagman contacts 13^a and 13^b, these lamps will remain lighted, and, as a result, the signals S^1 and S^2 instead 50 of having only the preliminary warning lamps lighted under these conditions, as was the case with the apparatus illustrated in Fig. 1 will have both the proceed and preliminary warning lamps lighted. When the 55 train enters section E—F, magnet 4^a of relay L^1 will become deenergized, which will cause front contacts 6^a and 7^a and flagman contact 13^a of this relay to become opened 60 and back contact 8^a to become closed. The opening of flagman contact 13^a will open the circuit for the proceed lamps G, and the opening of front contact 7^a will open the circuit 65 for the preliminary warning lamps Y, while the closing of contact 8^a will complete one of

the circuits for the stop lamps R. The proceed lamps G and preliminary warning lamps Y will therefore become extinguished, and the stop lamps R will become lighted. When the train enters section F—J, magnet 4^b of interlocking relay L^1 will become deenergized, and front contacts 6^b and 7^b of this relay will therefore open, but back contact 8^b will remain open and flagman contact 13^b will remain closed. The opening of front contact 6^b will deenergize magnet 4^b of interlocking relay L^2 , but this relay will not close its back contact 10^b. When the train has passed completely out of section E—F, magnet 4^a of interlocking relay L^1 will again become energized, and this will cause front contacts 6^a and 7^a and flagman contact 13^a to again become closed, and back contact 8^a to become open. Since contact 11 of track relay T^e is then closed, the closing of front contact 6^a will complete the circuit for magnet 4^a of interlocking relay L^2 , and this relay will open its back contact 10^a. The opening of back contact 8^a of interlocking relay L^1 will interrupt the circuit for the stop lamps R, and since flagman contact 13^b remained closed when magnet 4^b of interlocking relay L^1 became deenergized, the closing of flagman contact 13^a will complete a circuit for the proceed lamps G. The stop lamps R will therefore become extinguished and the proceed lamps will become lighted. When the train enters section J—K, track relay T^j will become deenergized, but this will not affect the remainder of the apparatus. When the train has passed completely out of section F—J, magnet 4^b of interlocking relay L^1 will become energized, so that front contacts 6^b and 7^b will again become closed. This also will have no effect on the remainder of the apparatus. When the train has passed out of section J—K, track relay T^j will pick up, and since front contact 6^b of relay L^1 is then closed, this will complete the circuit for magnet 4^b of interlocking relay L^2 . This magnet will then become energized, and the apparatus will be restored to its normal condition in which it is illustrated in the drawing.

If a train moving toward the left traverses 115 the stretch of track shown in Fig. 2, the operation of the apparatus will be substantially the reverse of that just described, and will be readily understood from an inspection of the drawing.

One advantage of apparatus embodying my invention is that it provides means whereby the indications commonly accepted and usually displayed at intersections of highways or streets can be applied at the point of intersection of highways with railways.

Although I have herein shown and described only two forms of apparatus embodying my invention, it is understood that various changes and modifications may be made 125 130

therein within the scope of the appended claims without departing from the spirit and scope of my invention.

Having thus described my invention, what I claim is:

1. In combination, a stretch of railway track divided into first, second, third and fourth successive sections; a highway intersecting said stretch at substantially the junction of said second and third sections, a first interlocking relay having one magnet connected with the rails of said second section and having the other magnet connected with the rails of said third section, a first track relay connected with the rails of said first section and a second track relay connected with the rails of said fourth section, four sources of track circuit current one connected with the rails of each section, a second interlocking relay having its one magnet controlled by said first track relay and said one magnet of said first interlocking relay and having its other magnet controlled by said second track relay and said other magnet of said first interlocking relay, and a highway crossing signal located at the intersection of said railway track and said highway and controlled by said two interlocking relays.
2. In combination, a stretch of railway track divided into first, second, third, and fourth successive sections; a highway intersecting said stretch at substantially the junction of said second and third sections, a first interlocking relay having one magnet connected with the rails of said second section and having the other magnet connected with the rails of said third section, a first track relay connected with the rails of said first section and a second track relay connected with the rails of said fourth section, four sources of track circuit current one connected with the rails of each section, a second interlocking relay having its one magnet controlled by said first track relay and said one magnet of said first interlocking relay and having its other magnet controlled by said second track relay and said other magnet of said first interlocking relay and said other magnet of said second interlocking relay for at other times causing said signal to display a second one of said indications and by said other magnet of said first interlocking relay and said other magnet of said second interlocking relay for at other times causing said signal to display a third one of said indications and by said other magnet of said first interlocking relay for at other times causing said signal to display said third indication.
3. In combination, a stretch of railway track divided into first, second, third, and fourth successive sections; a highway intersecting said stretch at substantially the junction of said second and third sections, a first interlocking relay comprising two magnets and front and back contacts controlled by each of said magnets, a second interlocking relay comprising two magnets and back and flagman contacts controlled by each of said magnets; a track circuit for said second section including one magnet of said first interlocking relay, a track circuit for said third section including the other winding of said first interlocking relay, a circuit for one magnet of said second interlocking relay including a front contact of said first track relay and a front contact controlled by said one magnet

other magnet of said first interlocking relay for controlling said stop lamp.

3. In combination, a stretch of railway track divided into first, second, third, and fourth successive sections; a highway intersecting said stretch at substantially the junction of said second and third sections, a first interlocking relay having one magnet connected with the rails of said second section and having the other magnet connected with the rails of said third section, a first track relay connected with the rails of said first section and a second track relay connected with the rails of said fourth section; four sources of track circuit current one connected with the rails of each section, a second interlocking relay having its one magnet controlled by said first track relay and said one magnet of said first interlocking relay and having its other magnet controlled by said second track relay and said other magnet of said first interlocking relay, a highway crossing signal capable of displaying three indications located at the intersection of said railway track and said highway, means controlled by both magnets of said second interlocking relay for causing said signal to display a first one of said indications, means controlled by said one magnet of said first interlocking relay and said one magnet of said second interlocking relay for at times causing said signal to display a second one of said indications and by said other magnet of said first interlocking relay and said other magnet of said second interlocking relay for at other times causing said signal to display a third one of said indications and by said other magnet of said first interlocking relay for at other times causing said signal to display said third indication.

4. In combination; a stretch of railway track divided into first, second, third, and fourth successive sections; a highway intersecting said stretch at substantially the junction of said second and third sections, a track circuit for said first section including a track relay, a track circuit for said fourth section including a second track relay, a first interlocking relay comprising two magnets and front and back contacts controlled by each of said magnets, a second interlocking relay comprising two magnets and back and flagman contacts controlled by each of said magnets; a track circuit for said second section including one magnet of said first interlocking relay, a track circuit for said third section including the other winding of said first interlocking relay, a circuit for one magnet of said second interlocking relay including a front contact of said first track relay and a front contact controlled by said one magnet

of said first interlocking relay, a circuit for the other magnet of said second interlocking relay including a front contact of said second track relay and a front contact controlled by said other magnet of said first interlocking relay, a highway crossing signal located adjacent the intersection of said stretch and said highway and provided with a proceed lamp, a preliminary warning lamp, and a stop lamp; a circuit for said proceed lamp including a flagman contact controlled by said one magnet of said second interlocking relay and a flagman contact controlled by said other winding of said second interlocking relay, a circuit for said preliminary warning lamp including a front contact controlled by said one winding of said first interlocking relay and a back contact controlled by said one winding of said second interlocking relay, and a circuit for said stop lamp including a back contact controlled by said one winding of said second interlocking relay, 10 and a circuit for said proceed lamp including a flagman contact controlled by said one magnet of said second interlocking relay and a flagman contact controlled by said other winding of said second interlocking relay, a circuit for said preliminary warning lamp including a front contact controlled by said one winding of said first interlocking relay and a back contact controlled by said one winding of said second interlocking relay, 15 and a circuit for said stop lamp including a back contact controlled by said one winding of said first interlocking relay connected in multiple with a back contact controlled by said other winding of said first interlocking relay, 20 and a circuit for said stop lamp including a back contact controlled by said one winding of said first interlocking relay connected in multiple with a back contact controlled by said other winding of said first interlocking relay, 25

5. In combination; a stretch of railway track divided into first, second, third and fourth successive sections; a highway intersecting said stretch at substantially the junction of said second and third sections, a first interlocking relay comprising two magnets and front and back contacts controlled by each of said magnets, a second interlocking relay comprising two magnets and back and flagman contacts controlled by each of said magnets; a track circuit for said second section including one magnet of said first interlocking relay, a track circuit for said third section including the other winding of said first interlocking relay, a circuit for one magnet of said second interlocking relay including a front contact of said first track relay and a front contact controlled by said one magnet of said first interlocking relay, a circuit for the other magnet of said second interlocking relay including a front contact of said second track relay and a front contact controlled by said other magnet of said first interlocking relay, a highway crossing signal located adjacent the intersection of said railway track and said highway and provided with a proceed lamp, a preliminary warning lamp, and a stop lamp; a circuit for said proceed lamp including a flagman contact controlled by said one magnet of said second interlocking relay and a back contact controlled by said one winding of said first interlocking relay, and a circuit for said preliminary warning lamp including a front contact controlled by said one winding of said second interlocking relay and a back contact controlled by said one winding of said first interlocking relay, and a circuit for said stop lamp including a back contact controlled by said one winding of said second interlocking relay, 10 and a circuit for said proceed lamp including a flagman contact controlled by said one magnet of said second interlocking relay and a flagman contact controlled by said other winding of said second interlocking relay, a circuit for said preliminary warning lamp including a front contact controlled by said one winding of said first interlocking relay and a back contact controlled by said one winding of said second interlocking relay, and a circuit for said stop lamp including a back contact controlled by said one winding of said second interlocking relay, 15 and a circuit for said proceed lamp including a flagman contact controlled by said one magnet of said second interlocking relay and a flagman contact controlled by said other winding of said second interlocking relay, a circuit for said preliminary warning lamp including a front contact controlled by said one winding of said first interlocking relay and a back contact controlled by said one winding of said second interlocking relay, and a circuit for said stop lamp including a back contact controlled by said one winding of said second interlocking relay, 20 and a circuit for said proceed lamp including a flagman contact controlled by said one magnet of said second interlocking relay and a flagman contact controlled by said other winding of said second interlocking relay, a circuit for said preliminary warning lamp including a front contact controlled by said one winding of said first interlocking relay and a back contact controlled by said one winding of said second interlocking relay, and a circuit for said stop lamp including a back contact controlled by said one winding of said second interlocking relay, 25

said second interlocking relay, a second circuit for said preliminary warning lamp including a front contact controlled by said other winding of said first interlocking relay and a back contact controlled by said other winding of said second interlocking relay, and a circuit for said stop lamp including a back contact controlled by said one winding of said first interlocking relay connected in multiple with a back contact controlled by said other winding of said first interlocking relay. 70

6. In combination, a stretch of railway track divided into first, second, third and fourth successive sections, a highway intersecting said stretch at substantially the junction of said second and third sections, a first interlocking relay having one magnet connected with the rails of said second section and having the other magnet connected with the rails of said third section, a first track relay connected with the rails of said first section and a second track relay connected with the rails of said fourth section, four sources of track circuit current one connected with the rails of each section, a second interlocking relay provided with two magnets, means for energizing one magnet of said second interlocking relay when and only when said first track relay and said one magnet of said first interlocking relay are both energized, means for energizing the other magnet of said second interlocking relay when and only when said second track relay and said other magnet of said first interlocking relay are both energized; a highway crossing signal located at the intersection of said railway track and said highway and comprising a proceed lamp, a preliminary warning lamp, and a stop lamp; means effective when both magnets of said second interlocking relay are energized for energizing said proceed lamp, means effective when said one magnet of said first interlocking relay is energized and said one magnet of said second interlocking relay is deenergized for at times energizing said preliminary warning lamp, means effective when said other magnet of said first interlocking relay is energized and said other magnet of said second interlocking relay is deenergized for at other times energizing said preliminary warning lamp, and means effective when either of said first interlocking relay becomes deenergized previous to the deenergization of the other magnet of this relay for energizing said stop lamp. 90

7. In combination, a stretch of railway track divided into first, second, third and fourth successive sections, a highway intersecting said stretch at substantially the junction of said second and third sections, a first interlocking relay having one magnet connected with the rails of said second section and having the other magnet connected with the rails of said third section, a first track relay con- 125

15 nected with the rails of said first section and a second track relay connected with the rails of said fourth section, four sources of track circuit current one connected with the rails of each section, a second interlocking relay provided with two magnets, means for energizing one magnet of said second interlocking relay when and only when said first track relay and said one magnet of said first interlocking relay are both energized, means for 20 energizing the other magnet of said second interlocking relay when and only when said second track relay and said other magnet of said first interlocking relay are both energized, a highway crossing signal located at the intersection of said railway track and said highway and comprising a proceed lamp, a preliminary warning lamp, and a stop lamp; means effective when both magnets of said first interlocking relay are energized for energizing said proceed lamp, means effective when said one magnet of said first interlocking relay is energized and said one magnet of said second interlocking relay is deenergized for at times energizing said preliminary warning lamp, means effective when both magnets of said first interlocking relay are energized for at times energizing said preliminary warning lamp, means effective when said other magnet of said first interlocking relay is energized and said other magnet of said second interlocking relay is energized for at other times energizing said preliminary warning lamp, and means effective when either magnet of said first interlocking relay becomes deenergized previous to the deenergization of the other magnet of the relay for energizing said stop lamp.

25 8. In combination, a stretch of railway track divided into first, second, third and fourth successive sections, a highway intersecting said stretch at substantially the junction of said second and third sections, a first interlocking relay having one magnet connected with the rails of said second section and having the other magnet connected with the rails of said third section, a first track relay connected with the rails of said first section and a second track relay connected with the rails of said fourth section, four sources of track circuit current one connected with the rails of each section, a second interlocking relay provided with two magnets, means for energizing one magnet of said second interlocking relay when and only when said first track relay and said one magnet of said first interlocking relay are both energized; a highway crossing signal located adjacent the intersection of said stretch and said highway and comprising a proceed lamp, a preliminary warning lamp, and a stop lamp; means effective when both magnets of said second interlocking relay are energized or when one magnet of said second interlocking relay has again become energized subsequent to the previous deenergization of both magnets for energizing said proceed lamp, means effective when said one magnet of said first interlocking relay is energized and said one magnet of said second interlocking relay is deenergized for at times energizing said preliminary warning lamp, means effective when said other magnet of said first interlocking relay is energized and said other magnet of said second interlocking relay is energized for at other times energizing said preliminary warning lamp, and means effective when either magnet of said first interlocking relay becomes deenergized previous to the deenergization of both magnets of said first interlocking relay

30 70 are energized or when one magnet of said first interlocking relay has again become energized subsequent to the previous deenergization of both magnets for energizing said proceed lamp, means effective when said one magnet of said first interlocking relay is energized and said one magnet of said second interlocking relay is deenergized for at times engaging said preliminary warning lamp, means effective when said other magnet of said first interlocking relay is energized and said other magnet of said second interlocking relay is deenergized for at other times energizing said preliminary warning lamp, and means effective when either magnet of said first interlocking relay becomes deenergized previous to the deenergization of the other magnet of the relay for energizing said stop lamp.

35 75 9. In combination, a stretch of railway track divided into first, second, third and fourth successive sections, a highway intersecting said stretch at substantially the junction of said second and third sections, a first interlocking relay having one magnet connected with the rails of said second section and having the other magnet connected with the rails of said third section, a first track relay connected with the rails of said first section and a second track relay connected with the rails of said fourth section, four sources of track circuit current one connected with the rails of each section, a second interlocking relay provided with two magnets, means for energizing one magnet of said second interlocking relay when and only when said first track relay and said one magnet of said first interlocking relay are both energized, means for energizing the other magnet of said second interlocking relay when and only when said second track relay and said other magnet of said first interlocking relay are both energized; a highway crossing signal located adjacent the intersection of said stretch and said highway and comprising a proceed lamp, a preliminary warning lamp, and a stop lamp; means effective when both magnets of said second interlocking relay are energized or when one magnet of said second interlocking relay has again become energized subsequent to the previous deenergization of both magnets for energizing said proceed lamp, means effective when said one magnet of said first interlocking relay is energized and said one magnet of said second interlocking relay is deenergized for at times energizing said preliminary warning lamp, means effective when said other magnet of said first interlocking relay is energized and said other magnet of said second interlocking relay is energized for at other times energizing said preliminary warning lamp, and means effective when either magnet of said first interlocking relay becomes deenergized previous to the deenergization of the other magnet of the relay for energizing said stop lamp.

the other magnet of this relay for energizing said stop lamp.

10. In combination; a stretch of railway track divided into first, second, third and fourth successive sections; a highway intersecting said stretch at substantially the junction of said second and third sections, a track circuit for said first section including a first track relay, a track circuit for said 10 fourth section including a second track relay; a first interlocking relay comprising a first and second magnet, a first and second contact controlled by said first magnet in such manner that said first and second contacts are closed when and only when said first magnet is energized, a third contact controlled by said first magnet in such manner that said third contact is closed when and only when said first magnet has become deenergized previous to the deenergization of said second magnet, a fourth and fifth contact controlled by said second magnet in such manner that said fourth and fifth contacts are closed when and only when said second magnet is energized, and a sixth contact controlled by said second magnet in such manner that said sixth contact is closed when and only when said second magnet has become deenergized previous to the deenergization of said first magnet; a track circuit for said second section including said first magnet, a track circuit for said third section including said second magnet; a second interlocking relay comprising a third and fourth magnet, a seventh contact controlled by said third magnet in such manner that said seventh contact is closed when and only when said third magnet has become deenergized previous to the deenergization of said fourth magnet, an eighth contact controlled by said third magnet in such manner that said eighth contact is closed at all times except when said third magnet becomes deenergized previous to the deenergization of said fourth magnet, a ninth contact controlled by said fourth magnet in such manner that said ninth contact is closed when and only when said fourth magnet has become deenergized previous to the deenergization of said third magnet, a tenth contact controlled by said fourth magnet in such manner that said tenth contact is closed at all times except when said fourth magnet has become deenergized previous to the deenergization of said third magnet, a circuit for said third magnet including a front contact of said first track relay and said first contact, a circuit for said fourth magnet including a front contact of said second track relay and said fourth contact; a highway crossing signal located adjacent the intersection of said railway track and said highway and provided with a proceed lamp, a preliminary warning lamp, and a stop lamp; a circuit for said proceed lamp including said eighth and tenth contacts, a

first circuit for said preliminary warning lamp including said second contact and said seventh contact, a second circuit for said preliminary warning lamp including said fifth and said ninth contacts, a first circuit for 70 said stop lamp including said third contact, and a second circuit for said stop lamp including said sixth contact.

11. In combination; a stretch of railway track divided into first, second, third, and fourth successive sections; a highway intersecting said stretch at substantially the junction of said second and third sections, a track circuit for said first section including a first track relay, a track circuit for said fourth section including a second track relay, a first interlocking relay comprising a first and second magnet, a first and second contact controlled by said first magnet in such manner that said first and second contacts are closed when and only when said first magnet is energized, a third contact controlled by said first magnet in such manner that said third contact is closed when and only when said first magnet has become deenergized previous to the deenergization of said second magnet, a fourth contact controlled by said first magnet in such manner that said fourth contact is closed at all times except when said first magnet becomes deenergized previous to the deenergization of said second magnet, a fifth and sixth contact controlled by said second magnet in such manner that said fifth and sixth contacts are closed when and only when said second magnet is energized, a seventh contact controlled by said second magnet in such manner that said seventh contact is closed when and only when said second magnet has become deenergized previous to the deenergization of said first magnet, and an eighth contact controlled by said second magnet in such manner that said eighth contact is closed at all times except when said second magnet becomes deenergized previous to the deenergization of said first magnet, a track 105 circuit for said second section including said first magnet, a track circuit for said third section including said second magnet; a second interlocking relay comprising a third and fourth magnet, a ninth contact controlled by said third magnet in such manner that said ninth contact is closed when and only when said third magnet has become deenergized previous to the deenergization of said fourth magnet, and a tenth contact controlled 110 by said fourth magnet in such manner that said tenth contact is closed when and only when said third magnet has become deenergized previous to the deenergization of said fourth magnet, and a circuit for said third magnet including a front contact of said first track relay and said first contact, a circuit for said fourth magnet including a front contact of said second track relay and said fourth contact; a highway crossing signal located adjacent 115 the intersection of said railway track and said highway and provided with a proceed lamp, a preliminary warning lamp, and a stop lamp; a circuit for said proceed lamp including said eighth and tenth contacts, a

the intersection of said railway track and said highway and provided with a proceed lamp, a preliminary warning lamp, and a stop lamp; a circuit for said proceed lamp including said fourth and eighth contacts, a first circuit for said preliminary warning lamp including said second contact and said ninth contact, a second circuit for said preliminary warning lamp including said sixth and said tenth contacts, a first circuit for said stop lamp including said third contact, and a second circuit for said stop lamp including said seventh contact.

12. In combination, a stretch of railway track intersected by a highway, a signal located at the intersection of said stretch and said highway, said signal being capable of displaying three indications, means effective when no train is approaching said highway on said stretch for causing said signal to display a first one of said indications, means effective when a train enters said stretch and until the train has passed a first point located a predetermined distance in rear of said highway for causing said signal to display a second one of said indications, and means effective after said train has passed said first point and until the train has passed the highway for causing said signal to display the third one of said indications.

13. In combination, a stretch of railway track intersected by a highway, a signal located at the intersection of said stretch and said highway, said signal being capable of displaying three indications, means effective when no train is approaching said highway on said stretch for causing said signal to display a first one of said indications, means effective when a train enters said stretch and until the train has passed a first point located a predetermined distance in rear of said highway for causing said signal to display a second one of said indications, means effective after said train has passed said first point and until the train has passed the highway for causing said signal to display the third one of said indications, and means effective after said train has passed said highway for causing said signal to again display said first indication.

14. In combination, a stretch of railway track over which traffic moves in both directions, said stretch being intersected at an intermediate point by a highway, a highway crossing signal capable of displaying three indications located adjacent the intersection of said stretch and said highway, means effective when said stretch is unoccupied for causing said signal to display a first one of said indications, means effective when a train moving in either direction enters said stretch and until said train is within a predetermined distance from said highway for causing said signal to display a second one of said indications, and means effective after said

train is within said predetermined distance from said highway and until after the train has passed said highway for causing said signal to display the third one of said indications.

15. In combination, a stretch of railway track over which traffic moves in both directions, said stretch being intersected at an intermediate point by a highway, a highway crossing signal capable of displaying three indications located adjacent the intersection of said stretch and said highway, means effective when said stretch is unoccupied for causing said signal to display a first one of said indications, means effective when a train moving in either direction enters said stretch and until said train is within a predetermined distance from said highway for causing said signal to display a second one of said indications, means effective after said train is within said predetermined distance from said highway and until after the train has passed said highway for causing said signal to display the third one of said indications, and means effective as soon as said train has passed beyond said highway for again causing said signal to display said first indication.

16. In combination, a stretch of railway track over which traffic moves in both directions, said stretch being divided into first, second, third and fourth successive sections, a highway intersecting said stretch at substantially the junction of said second and third sections, a highway crossing signal capable of displaying three indications located adjacent the intersection of said stretch and said highway, means effective when all of said sections are unoccupied for causing said signal to display a first one of said indications, means effective when either said first or said fourth section is occupied by a train approaching said highway for causing said signal to display a second one of said indications, and means effective when either said second or said third section is occupied by a train approaching said highway for causing said signal to display a third one of said indications.

17. In combination, a stretch of railway track over which traffic moves in both directions, said stretch being divided into first, second, third and fourth successive sections, a highway intersecting said stretch at substantially the junction of said second and third sections, a highway crossing signal capable of displaying three indications located adjacent the intersection of said stretch and said highway, means effective when all of said sections are unoccupied for causing said signal to display a first one of said indications, means effective when either said first or said fourth section is occupied by a train approaching said highway for causing said signal to display a second one of said indications, and means effective when either said second or

said third section is occupied by a train approaching said highway for causing said signal to display a third one of said indications, and means effective after the train has passed
5 said highway for again causing said signal to display said first indication.

18. In combination, a stretch of railway track divided into four successive sections, a highway crossing said stretch adjacent the
10 junction of the two inner sections, a first interlocking relay having two magnets controlled by traffic conditions in said two inner sections respectively, two track relays controlled by traffic conditions in the two outer sections
15 respectively, a second interlocking relay having two magnets one controlled by one magnet of said first interlocking relay and by one track relay and the other controlled by the remaining magnet of said first interlocking
20 relay and by the other track relay, and a signal controlled by said two interlocking relays.

In testimony whereof I affix my signature.

CHARLES W. BELL.
